Application January 21, 1953, Serial No. 332,381

9 Claims. (Cl. 81—52.4)

This invention relates to chuck opening and closing mechanism. Chucks are commonly provided with one or more sockets for the reception of a mating wrench, by the turning of which the jaws of the chuck are moved to clamp or release the work. If the work piece be of substantial diameter, the power required to open or close the chuck may be considerable so that manual turning of the wrench is not feasible, more particularly when opening the chuck. There are also great differences in the amount of power required under different conditions and for work pieces of different diameters and materials. For these reasons variable torque control of an actuating wrench is highly desirable and this invention has for one object to utilize such a control.

A further object is to provide an apparatus for the purpose which may be at all time available for its intended purpose though normally out of position to interfere in any way with the normal use of the chuck.

This invention provides means, therefore, by which the wrench is in normally retracted condition out of contact with the chuck, but which may be caused to move into operative relation thereto when desired in an easy and expeditious manner.

It also provides means by which the wrench or turning member is guided into operative relation to the chuck, and when in position may begin to turn the rotary element with a blow sufficiently hard to release any sticking of the chuck parts. This is important, particularly when it is desired to open the chuck to release a work piece as the work piece is often so tightly gripped at that time that a releasing blow is necessary in order to start opening the chuck.

It also provides for automatic stopping of the wrench advance after a predetermined amount of advance thereof sufficient to properly engage the wrench with the chuck opening and closing means, and an automatic stopping of the retraction of the wrench at a predetermined retracted position.

For a complete understanding of this invention, reference may be had to the accompanying drawings in which

Figure 1 is a central longitudinal sectional view through the operator mechanism in idle condition, a portion of the chuck being shown in position for the chuck to be opened or closed thereby.

Figures 2 to 6, inclusive, are detail sectional views on the correspondingly numbered section lines of Figure 1.

Figure 7 is a view similar to a portion of Figure 1, but to a larger scale and with the parts shown in different positions.

Figure 8 is a detail sectional view on line 8—8 of Figure 6.

Referring to Figure 1, the chuck opening and closing wrench mechanism of the present invention comprises a casing 1 to which is secured, as by bolts 2, a bracket 3 having a pair of spaced split strap portions 4 formed to engage about and be suspended from a stationary bar 5. These straps 4 may be keyed to the bar as by a key 6 (see Figure 1) and may be clamped thereto by tightening

2

bolts 7 which engage opposite ends of the split portions. By this means of suspension the wrench is supported with a shaft extension 10 thereof in position to be moved into and out of engagement with a rotary opening and closing member 11 of a chuck 12 mounted in operative position on a suitable lathe or other device to which the bar 5 is secured. As shown in Figure 1, this member 11 is a rotary shaft having a bevel gear portion 13 mating with bevel gear teeth 14 on the rotating element of a spiral clutch which may be of any well known type, it being apparent that by rotating the member 11 in the proper direction, the chuck may be opened or closed as desired.

The shaft extension 10 is a reduced diameter portion of a shaft member 15. The rear end of this shaft 15 is provided with a pair of spaced collars 16 and 17, between which there is journaled thereon, an externally threaded sleeve 18, and engaging the threads of this sleeve 18 is a nut element 20. This nut element 20 is provided with means by which it may be rotated in either direction while held against axial motion, thus to move the sleeve 18 and the shaft 15 axially. As shown this means comprises a reversible motor having the rotor 21 carried by the nut 20 and having a stator at 22. The rotor and the nut 20 are held against axial motion, the nut being mounted in axially spaced ball bearings 23 and 24. The outer end portion of the sleeve 18 is formed cup shaped as at 25 and houses the end collar 16 carried by the shaft 15, these collars 16 and 17 preventing relative axial motion between the shaft 15 and the sleeve 18. The portion 25 also carries on its inner face a ball bearing 26 (see Figure 8) which supports the outer end of the shaft 15 so that this shaft 15 may rotate relative thereto.

The sleeve 18 is held against rotation by key portions 27 on the portion 25 (see Figures 7 and 8) which ride in longitudinal slots 28 in a cylindrical casing member 29 which is connected to the casing 1 through the intermediate cylindrical casing 30—31 and 32.

The portion 25 also carries a shoulder 33 (see Figures 1 and 8) which is adapted to contact with a reversely positioned shoulder 35a of an arm 35 mounted for axial motion within the casing 29 and which extends into an end enclosure 36 where are positioned a pair of limit switches 37 and 38. The limit switch 37 is normally closed, but may be opened by pressure against the stem 37a therein of a lever 39 fulcrumed at 40 on the enclosure wall 41 and pivoted at 42 to the end portion of the bar 35. Thus when the nut 20 by its rotation has moved the shaft 15 and the parts carried thereby to the right, as viewed in Figures 1 and 8, to a desired limit, the shoulders 33 and 35a contacting, move the bar 35 toward the right and swings the lever 39 to open the limit switch 37. This is when the shaft extension 10 has fully entered the socket in the member 11. Similarly the switch 38 is opened by the member 25 engaging and pressing outwardly a stop pin 40 slideable through the wall 41 and engaging the stop switch element 42, this taking place when the shaft 15 is retracted to its desired outward limit where it does not engage the chuck.

These switches 37 and 38 are in the control circuits to the reversible motor having the rotor 21 and the stator, and are so arranged, as is well known in the art, that when the rotor is rotating in one direction causing the shaft 15 to be moved axially, this rotation is stopped when the corresponding limit switch is opened.

The shaft extension 10 has slidably keyed thereon a wrench sleeve 50 having a pair of diametrically opposed wing elements 52 which may be engaged in suitable socket portions 53 extending diametrically outwardly from a central cylindrical socket portion 54 of the chuck element 11. The shaft extension 10 is of sufficiently small diameter to pass freely into the socket 54, but the wings 52 may engage within the outer portion of this

socket only when they are in position to pass between the lugs 53 of the element 11. The wrench element 50 is normally pressed forwardly as far as permitted by a transverse pin 56 seated in a transverse hole through the enlarged diameter portion 57 of the shaft 15 and riding in a slot 58 in diametrically opposite sides of the wrench element 50. When the shaft 15 is moved endwise toward the clutch element 11, when this clutch element is improperly angularly positioned to receive the extension 10 within the socket 54, the wrench element may be pushed backward against the pressure of the spring 59 until such time as the rotation of the shaft 15 brings the lugs 52 into position to pass into the outer portion of the socket, whereupon the spring 59 projects the wrench element into position, and further rotation of the shaft 15 also rotates the element 11.

The shaft 15, as shown, is rotated by a motor having a quill 60 through which the shaft 15 passes, this quill being journaled at its end portions in the ball bearings 61 and 62. As shown in Figure 1, this quill 60 has fixed thereto a pair of motor rotors 63 and 64 which have corresponding stators 65 and 66 carried by the casing member 32. These rotors 63 and 64 are preferably rotors of poly-phase induction motors connected up as shown in the Seeger and Stansbury Patent No. 2,312,592 granted March 2, 1943, forming two motors having either the same or different synchronous speeds and having the same or different speed torque characteristics, and as shown and described in this patent, they may be operated either cumulatively, that is, tending to rotate in the same direction, or differentially, whereby one motor tends to rotate oppositely to the direction of rotation of the other motor. Also the voltage impressed upon one motor relative to the voltage impressed upon the other motor may be varied so that it is possible to still further vary the combined speed torque characteristics of the motors.

By this method of control the power for rotating the motors may be adjusted in accordance with the size of the work piece engaged by the chuck, it being understood that these motors act to rotate the shaft 15, thereby to open or close the chuck. The shaft 15 is rotated by these two motors through a reduction gear. Thus the quill 60 carries an end pinion portion 70 which meshes with each of three gears 71, and to each of these gears there is fixed a small gear 72 which meshes with the teeth of an internal gear 73 having a hub portion 74 (see Figure 1) keyed to a sleeve 75, which, in turn, is splined to a portion 76 of the shaft 15. The hub 74 is positioned between the segmental collar 79 integral with the sleeve 75 and a bearing partition 77 in which one end of each of the shafts 78 which carry the gear units 71 and 72 is journaled. The opposite ends of the shafts 78 are journaled in the opposite integral end wall of the casing 1. This member 77 is fixed to the end wall of the stationary casing member 1 as by means of the bolts 80. The sleeve 75 is journaled within the ball bearing 81 which is held in fixed axial position by the cap member 82 fixed as by bolts 83 to the member 1.

From an inspection of Figure 2, it will be noted that there is a lost motion connection between the motor rotor 21 and the nut member 20, the rotor having angularly spaced lugs 86 which extend between lugs 87 of the nut member 20. This provides for the rotation of the rotor 21 to produce a blow against the nut member, thus to start the axial motion of the shaft 15. There is a similar lost motion connection between the wrench element 50 and the socket member 11, and between the internal gear 74 and the sleeve 75, as shown particularly in Figure 3 where the segments of collar 79 are shown as extending between and normally spaced from a pair of lugs 89 on the member 74 to produce a starting rotational blow on the clutch element 11.

When it is desired to employ the power wrench member for either closing or opening the chuck, the spindle carrying the chuck is first moved to a position where

one of the elements 11 is approximately in alignment with the shaft 15, whereupon the motor 22 is operated in a direction to move the shaft 15 axially into engagement with the element 11. The shaft 15 is then rotated in accordance with the desired direction and torque by control of the alternating current motors for the rotors 63 and 64. As soon as the wrench element may find its position within the outer portion of the chuck socket, it snaps thereto, whereupon further rotation is effective to open or close the chuck. The inward motion of the shaft 15 is stopped by the opening of the limit switch 37 and its outward motion by the opening of the limit switch 38.

The motors having the rotors 63 and 64 may continue to rotate until they are stalled by the opening or closing of the chuck to its limit, the closing movement, of course, being determined by the closing of the chuck jaws onto the work piece. Removal of the wrench after such a closing or opening of the chuck is produced by actuating the motor having the rotor 21 in the reverse direction to pull the wrench away from engagement with the chuck element 11.

From the foregoing description of an embodiment of this invention it should be evident to those skilled in the art that various changes and modifications may be made without departing from its spirit or scope.
